UNITED STATES PATENT OFFICE.

LEE COLLIER ROSS, OF WEST POINT, MISSISSIPPI.

FIRE DOG OR IRON.

No. 853,831.

Specification of Letters Patent.

Patented May 14, 1907.

Application filed May 31, 1906. Serial No. 319,559.

To all whom it may concern:

Be it known that I, LEE COLLIER Ross, a citizen of the United States, and a resident of West Point, in the county of Clay and State of Mississippi, have invented certain new and useful Improvements in Fire Dogs or Irons, of which the following is a specification.

My invention relates to improvements in fire dogs designed to be used in open fireplaces, and has for its object to provide simple, cheap and efficient means for holding the burning wood in the fire place and preventing its falling out on the hearth; also to provide simple, efficient and convenient means for heating irons or other articles by the fire.

To these ends my invention consists in combining two fire irons or dogs with a connecting plate upon which irons etc. are to be placed to be heated.

My invention consists further in certain novel features of construction, arrangement and combination of parts as will be herein-after fully described and pointed out in the claims, reference being had to the accompanying drawing, in which

Figure 1 is a perspective view showing an open fire place with my improvements as in use. Fig. 2 is a vertical section on line 2—2 of Fig. 1. Fig. 3 is a fragmentary sectional elevation. Fig. 4 is a vertical section on line 4—4 of Fig. 1.

In carrying out my invention I use two dogs A made of iron or other suitable material, each being provided with a single removable front leg A', and a bifurcated removable leg A² at the rear of the dog. Near the front end of each dog are provided in the side faces the grooves or channels a, one pair 40 of which are disposed vertically, as the central ones, while those in front and rear of said vertical grooves are disposed at an angle as shown in Figs. 1 and 2.

In connection with each dog I use a staff B, the lower end of which is bifurcated, said bifurcated lower end fitting over the dog and in the grooves on each side of the dog; each staff is provided near its upper end with a hole b in which a hook or poker may be inserted to remove the staff to change from one set of grooves to another set. Removably secured to the front face of each staff at their inner edge, by bolts b' is a plate C having a horizontal flange or ledge c at its lower end; these plates B extend inwardly and overlap, 55 one of said plates being provided with a turn-

button c' which passes through a horizontal slot c² in the other plate, so that the plates may be connected at their inner ends and moved in or out to adjust the device to varying widths of fireplaces. These plates when connected together form a practically continuous ledged plate upon which flatirons may be placed, as indicated in dotted lines Fig. 2, whereby the irons may be heated by the burning wood placed on the dogs back of the staffs.

In the position of the staffs shown in Figs. 1 and 2 they will bear upon the pieces of wood and prevent them from falling outward on the hearth. If a larger amount of wood is to be piled on the dogs, the staffs may be placed in the vertical grooves of the dogs; and if an extra large amount of wood is to be used the staffs may be placed in the front inclined set of grooves, the inclination of which is at an opposite angle to that of the rear set of grooves.

As the legs of the dogs are removable and the plates detachable from each other and from the staffs it will be seen that the device can be readily taken apart and stowed away in a small space.

It will also be observed that by the use of my invention, the burning wood will be prevented from falling outward onto the hearth and causing a conflagration. Furthermore with the plates in position the danger of women or children having their skirts get into the fire is reduced to a minimum.

I claim—

1. In a device of the character described, a pair of dogs, a staff removably attached to each dog, and a vertical plate connecting said staffs.

2. In a device of the character described, a pair of dogs, a staff removably attached to each dog, a vertical plate extending inwardly from each staff, and means for detachably connecting the free ends of said plates.

3. In a device of the character described, a pair of dogs, a staff adjustably attached to each dog, a plate detachably secured to the inner edge of each staff extending inwardly toward each other and adapted to overlap, and means for adjustably and removably connecting said overlapping ends.

4. In a device of the character described, a pair of dogs, each dog provided near its front end with a series of grooves on its side faces disposed at different angles, a bifurcated staff adapted to fit in said grooves, a flanged

plate detachably secured to the inner edge of each plate, said plates extending inwardly toward each other and adapted to overlap, and means for removably and adjustably connecting said overlapping ends.

5. In a device of the character described, a pair of dogs, removable legs at the front and rear ends of the said dogs, each dog having a series of grooves in its side faces near its front end arranged at different angles, a bifurcated

staff adapted to fit in the said grooves of each dog, a plate having a flange at its lower edge, detachably secured to the inner edge of each staff and extending inwardly toward each other and overlapping, and means for adjustably connecting said overlapping ends.

15
LEE COLLIER ROSS.
